United States Patent Office

Des. 182,732
Patented May 6, 1958

182,732

SHUFFLEBOARD

Thomas La Salle and John Perec, Utica, N. Y.

Application July 26, 1955, Serial No. 37,135

Term of patent 3½ years

(Cl. D34—5)

Fig. 1

Fig. 2

Fig. 3

Fig. 4

Fig. 5

Fig. 6

Figure 1 is a top plan view of a shuffleboard, showing our new design;

Figure 2 is a bottom plan view;

Figure 3 is a side elevational view, the opposite side having substantially the same appearance;

Figure 4 is an end elevational view, the opposite end having substantially the same appearance;

Figure 5 is a perspective view; and

Figure 6 is a fragmentary cross-sectional view thereof, to an enlarged scale, and partially broken away for convenience in illustration.

We claim:

The ornamental design for a shuffleboard, as shown and described.
